UNITED STATES PATENT OFFICE.

PHILIP S. MEDART, OF ST. LOUIS, MISSOURI, ASSIGNOR TO FRED MEDART MANUFACTURING COMPANY, OF ST. LOUIS, MISSOURI, A CORPORATION OF MISSOURI.

CASTER MECHANISM FOR VAULTING-HORSES.

1,076,778.

Specification of Letters Patent.

Patented Oct. 28, 1913.

Application filed May 11, 1912. Serial No. 696,616.

To all whom it may concern:

Be it known that I, PHILIP S. MEDART, a citizen of the United States of America, and a resident of the city of St. Louis, in the State of Missouri, have invented certain new and useful Improvements in Caster Mechanism for Vaulting-Horses, of which the following is a specification.

This invention relates to that particular class of exercising apparatus generally known as vaulting horses and bucks, and has for its object to provide a simple and efficient caster mechanism adapted to render the apparatus readily transportable when required, and which is housed within the floor plate or base of the apparatus and entirely out of the way in the ordinary use of the apparatus for exercising purposes, all as will hereinafter more fully appear.

In the accompanying drawings: Figure 1, is a detail horizontal section on line α — α , Fig. 2, of an apparatus embodying the present improvements. Fig. 2, is a detail central vertical section of the same.

Similar reference numerals indicate like parts in both views.

Referring to the drawings, 1 represents the central portion of the supporting base or floor plate of the apparatus formed with an open bottom cavity or chamber 2 for the reception and inclosure of the hereinafter described caster mechanism. Said central portion of the supporting base 1 is provided with the usual integrally formed radial or side supporting wings which are recessed on their under sides to attain the proper degree of lightness combined with strength, as usual in the present type of apparatus.

3 is a central annular neck extending vertically from the central portion 1 of the supporting base and having a cylindrical bore for the reception of the attaching shank of the post or pillar now to be described.

4 is the vertical post or pillar upon the upper end of which is mounted in any ordinary and suitable manner the vaulting horse or buck body. At its lower end said post is formed with a reduced cylindrical shank 5 adapted to have a driven fit in the cylindrical bore of the annular neck 3 aforesaid with its offset or shoulder abutting against the upper surface of the neck 3, to stop further downward movement of the post. In the present construction the diameter of the post 4 and that of the annular

neck 3 are approximately the same, in order to attain a substantially smooth exterior where the parts meet when assembled, and as shown in Fig. 2.

6 is a cylindrical extension depending from the cylindrical shank 5, into the interior of the cavity or chamber 2 of the supporting base, to provide a trunnion or support for the caster mechanism now to be described.

7 is a sleeve journaled on the cylindrical extension 6 aforesaid, and provided near its upper end with a gear rim 8, and on the periphery of its lower portion with a screw-thread 9, as illustrated in Fig. 2.

10 is an internally screw-threaded hub having operative engagement with the aforesaid screw-threaded portion 9 of the sleeve 7, and so that in the rotation of said sleeve in manner hereinafter described, the said hub will have a vertical rise or fall in accordance with the direction of rotation of the said sleeve. In the present construction the hub 10 carries the central depressed web of the caster-carrying frame 11 which is arranged horizontally in the open bottom cavity or chamber 2 of the supporting base, and the wheel casters 12 of any usual and suitable form are attached to the under side of the raised side plates or wings 13 of the carrying frame 11, as shown.

14 is a vertical guide spline on the supporting base 1 for engagement in a side notch of the caster carrying frame 11, to hold the same against rotation.

15 is a vertical countershaft journaled in a bearing formed therefor in the top plate of the chamber 2, aforesaid. 16 is an operating handle on the upper end of said countershaft, and 17 is a gear wheel secured to the lower end of said countershaft and having operative engagement with the above described gear rim 8 of the sleeve 7. The construction is such that with a manual rotation of the handle 16 in one direction or the other, corresponding rotation is imparted to the sleeve 7. Such rotation of the sleeve 7 will in turn impart an upward or a downward adjustment to the caster carrying frame 11, through the before described screw-thread connection of the sleeve 7 and 10, to bring the casters into an active or inactive position in accordance with the direction in which the operating handle 16 is turned.

Having thus fully described my said invention what I claim as new and desire to secure by Letters Patent, is:—

1. In a vaulting horse or buck, the combination of a supporting base formed on its underside with a recess adapted to receive a caster mechanism and having an integrally formed and centrally disposed neck which in turn is formed with a cylindrical bore 5 open at top and bottom, and a vertical post having a reduced cylindrical shank at its lower end fitting the cylindrical bore of the aforesaid neck and adapted to provide a supporting means for a caster mechanism, the offset or shoulder of the post abutting against the upper surface of the aforesaid neck, substantially as set forth.
2. In a vaulting horse or buck, the combination of a supporting base having an open bottom cavity at its center and an annular post receiving neck on its upper surface, a vertical post having a reduced cylindrical shank fitting the bore of said neck, a fixed trunnion in axial alinement with said shank, 25 a sleeve journaled on said trunnion and having a screw-thread on its periphery, means for imparting rotation to said sleeve, a frame having a screw-threaded hub engaging the screw-threaded periphery of the sleeve, and a series of casters carried by said frame, substantially as set forth.
3. In a vaulting horse or buck, the combination of a supporting base having an open bottom cavity at its center and an annular post receiving neck on its upper surface, a vertical post having a reduced cylindrical 30 shank fitting the bore of said neck, a fixed trunnion in axial alinement with said shank, a sleeve journaled on said trunnion and having a screw-thread on its periphery, means for imparting rotation to said sleeve, a frame having a screw-threaded hub engaging the screw-threaded periphery of the sleeve, and a series of casters carried by said frame, substantially as set forth.
4. In a vaulting horse or buck, the combination of a supporting base having an open bottom cavity at its center and an annular post receiving neck on its upper surface, a vertical post having a reduced cylindrical 35 shank fitting the bore of said neck, a fixed trunnion in axial alinement with said shank, a sleeve journaled on said trunnion and having a screw-thread on its periphery, means for imparting rotation to said sleeve, a frame having a screw-threaded hub engaging the screw-threaded periphery of the sleeve, and a series of casters carried by said frame, substantially as set forth.

shank fitting the bore of said neck, a fixed trunnion in axial alinement with said shank, a sleeve journaled on said trunnion and having a screw-thread on its periphery, means 40 for imparting rotation to said sleeve, the same comprising a gear rim on said sleeve, a gear wheel engaging said gear rim, a countershaft carrying said gear wheel and an operating handle on said countershaft, a 45 frame having a screw-threaded hub engaging the screw-threaded periphery of the sleeve, and a series of casters carried by said frame, substantially as set forth.

4. In a vaulting horse or buck, the combination of a supporting base having an open bottom cavity at its center and an annular post receiving neck on its upper surface, a vertical post having a reduced cylindrical shank fitting the bore of said neck, a fixed 50 trunnion in axial alinement with said shank, a sleeve journaled on said trunnion and having a screw-thread on its periphery, means for imparting rotation to said sleeve, a frame having side wings and a sunken center carrying a screw-threaded hub engaging the screw-threaded periphery of the sleeve, and a series of casters secured to the underside of the raised side wings of the said frame, substantially as set forth.

Signed at St. Louis, Missouri, this 30th day of April, 1912.

PHILIP S. MEDART.
